UNITED STATES PATENT OFFICE.

PHILIP LANGE, OF PITTSBURG, PENNSYLVANIA, ASSIGNOR TO THE WESTINGHOUSE ELECTRIC COMPANY, OF SAME PLACE.

ELECTRIC INDICATOR.

SPECIFICATION forming part of Letters Patent No. 434,154, dated August 12, 1890.

Application filed May 15, 1890. Serial No. 351,945. (No model.)

To all whom it may concern:

Be it known that I, PHILIP LANGE, a citizen of the United States, residing in Pittsburg, in the county of Allegheny and State of Pennsylvania, have invented a certain new and useful Improvement in Electric Indicator and Core for Same, (Case No. 366,) of which the following is a specification.

The invention relates to the construction of indicators for electric currents.

The object of the invention is to provide a device which will produce a continuous deflection of an indicating-arm and give equal deflections for corresponding changes in the current throughout a considerable range.

The invention involves especially the construction of the core for a solenoid, and this core is useful for other purposes than indicating devices, but will be described in connection therewith. The core is constructed of sections of magnetizable material separated from each other longitudinally by spaces and carried by a suitable support.

In the accompanying drawings, Figure 1 shows an electric indicator involving the features of the invention. Fig. 2 is an enlarged view of the core.

Referring to the figures, A represents a frame, upon which the parts of the instrument are supported.

35 B represents a solenoid, designed to be connected in an electric circuit, as indicated by the wires 1 and 2. The wire 2 leads to an adjustable resistance-coil C of well-known construction.

The indicating-arm E is carried upon a pivoted beam F. One end of this beam carries the core G, and a counterpoise H is suspended from the other end of the beam. The distance 40 to which the core will be drawn into the solenoid is dependent upon the difference of potential applied to the coil B.

The core is constructed of sections g, of soft

iron, supported at intervals along a rod g'. This rod may be of magnetizable material, or 45 in some instances it may be desirable to construct it of non-magnetizable material. In practice it is found that a core of this construction will afford an approximately equal pull upon the beam for equal increments of 50 potential throughout a considerable range.

A leveling-plumb is shown at K for adjusting the position of the instrument, so that when at rest the indicator E will be at the central point p of the index-card P. 55

I claim as my invention—

1. In an electric indicator, a solenoid and a core therefor, consisting of sections of magnetizable material, said sections being of such length and separated such distances that several sections may be contained within the core at any time, and a rigid rod upon which the sections are supported apart from each other in a longitudinal series, substantially as described. 65

2. In an electric indicator, the combination of the indicator-arm, the pivoted support therefor, the solenoid, the core carried by said support and entering said solenoid and consisting of sections of magnetizable material 70 separated from each other and arranged in a series concentric with the solenoid, and the counterpoise for the core.

3. A core for electrical devices, consisting of sections of magnetizable material and a 75 stiff rod or support, upon which the sections are arranged in a longitudinal series and separated from each other, substantially as described.

In testimony whereof I have hereunto subscribed my name this 5th day of May, A. D. 80 1890.

PHILIP LANGE.
